United States Patent Office.

SAMUEL W. JONES, OF BLUFFTON, INDIANA.

Letters Patent No. 66,850, dated July 16, 1867.

IMPROVEMENT IN PRUNING-SHEARS.

The Schedule referred to in these Letters Patent and making part of the same.

TO ALL WHOM IT MAY CONCERN:

Be it known that I, SAMUEL W. JONES, of Bluffton, in the county of Wells, and State of Indiana, have invented a new and useful Improvement in Pruning-Shears; and I do hereby declare the following to be a full, clear, and exact description of the same, reference being had to the accompanying drawings, forming part of this specification, and in which—

Figure 1 is a side elevation of my invention.

In this invention, the shears, fixed on the end of a staff, are operated by two levers connected by rods with each other and with the movable blade of the shears.

In the drawings, A A' represent the blades of the shears pivoted at *a*, one blade, A, having a shank, B, by which it is fixed firmly to the end of the staff C, the other, A', movable, and having its end opposite to the cutting-end connected with the operating-rod. F is a sliding-thimble *e*, clasping the staff C and moving up and down upon it, having a set-screw, *l*, by which it may be fixed in any required position on the staff. On one side of the thimble F are lugs in which, upon a pin, K, pivots a lever, D. The lower end of the staff C has a slot, through which passes a hand-lever, H, pivoted on a pin, *i*, in the slot. Instead of a slot and pin thus described, a simple pin, fixed in the side of the staff, may be used, or any other of the common means for pivoting such a lever. One end, *h*, of the lever H is shaped as a handle; the other has a link or eye, which holds the end of a connecting-rod running from the lever H to the lever D. *m m m* are holes in the lever D, at different distances from the staff E, in which the connecting-rods *e e'* may be hooked. By changing these rods from one of said holes to another, various degrees of power may be given to the cutting-shears A A'.

These pruning-shears are operated by the handle, *h*, which communicates by the connecting-rods *e e'* and lever D with the movable blade A', as above explained. By depressing the handle *h*, the shears are opened; by elevating it again, the shears are closed. Any required degree of power may be given to the instrument by means of the adjustable lever D. Shears thus constructed, although specially adapted to the pruning of vines, trees, and shrubbery, may be used for any other purpose for which stout shears are employed.

Having thus described my invention, what I claim as new, and desire to secure by Letters Patent, is—

1. The pruning-shears above described, having the fixed blade A attached to the staff C, and operating in combination with the movable blade A', the connecting-rods *e e'*, and the levers D and H, substantially as and for the purpose described.

2. The movable lever D, pivoting in a sliding-thimble, F, on the staff C, and having the holes *m m m*, by which its power may be adjusted, substantially as and for the purpose specified.

SAMUEL W. JONES.
